UNITED STATES PATENT OFFICE.

HARRY B. CHALMERS, OF NEW YORK, N. Y.

BOX.

Application filed January 25, 1924. Serial No. 688,388.

This invention relates to receptacles or boxes.

The invention more particularly relates to receptacles especially adapted for packaging articles for shipment and the box or receptacle hereinafter described is adapted for many uses, such as packaging fragile articles such as eggs, lamp bulbs and also for packaging candy, spools of thread, etc.

10 The invention has for its salient object to provide a receptacle or box that is rugged in construction and is adapted to withstand rough usage such as that received in shipping.

15 Another object of the invention is to provide a receptacle having a plurality of compartments and furthermore a construction that can be economically manufactured.

Another object of the invention is to provide 20 a receptacle so constructed and arranged that the covers or the ends thereof can be easily secured and sealed in closed position thereby easily rendering possible the detection of any tampering or opening of 25 the receptacle.

Further objects of the invention will appear 30 from the following description taken in connection with the drawings which form a part of this application and in which,

Fig. 1 is an elevational view, partly broken away and partly in section, showing a receptacle constructed in accordance with the invention.

Fig. 2 is a transverse sectional elevational 35 view taken substantially on line 2-2 of Fig. 1.

Fig. 3 is a top plan view of a blank which when folded forms a cover for one end of the receptacle.

Fig. 4 is a plan view showing the blank in 40 Fig. 3, folded.

Fig. 5 is a transverse sectional elevation taken on substantially on line 5-5 of Fig. 4.

Fig. 6 is a transverse sectional elevation 45 of another shape of box constructed in accordance with the invention, and

Fig. 7 is a top plan view on a reduced scale showing one of the spacing discs used in the form of receptacle illustrated in Fig. 1.

50 The invention briefly described consists of a box or receptacle having a plurality of compartments therein preferably formed of tubular members. These tubular members are secured within a sheath or binder which

55 tightly encloses the members. The two ends of the receptacle are closed by means of

covers and the covers are secured in position by tabs extending substantially at right angles to the body portion of the cover and projecting into wedge shaped spaces or openings formed between the binder or sheath and the tubular members. These projections are tightly wedged in the spaces thus firmly securing the covers in position. The receptacle may comprise a single section such as 60 shown in Fig. 6 or a plurality of longitudinally spaced sections as illustrated in Fig. 1. In order to form a seal for the ends of the receptacle a cord may be passed through the central tubular member (see Fig. 3) and 65 the ends of the cord secured together on the outside of the sheath or binder. A label or seal can then be pasted or otherwise secured over the ends of the cord. Further details 70 of the invention will appear from the following description.

In the form of the invention illustrated 75 the receptacle has seven compartments, six of the compartments as shown at 15 being grouped around and radially disposed with respect to a central compartment 16. It should be understood however, that the invention is not limited to any particular number of compartments. The compartments 15 and 16 are formed of tubular members 80 and these members may be secured in the position shown in Fig. 3 by placing the tubular members 15 upon a flat surface upon a cord or tape, placing the member 16 upon the members 15. Then by drawing the ends 85 of the cord together, the tubular members 15 will be grouped about the member 16 as shown in Fig. 3. If desired the member 16 may be coated with some adhesive substance 90 such as glue and thus as the members 15 are grouped around the central member they 95 will be secured thereto.

After the tubular members have been assembled in the manner shown in Fig. 2 a binder or sheath 17 is wrapped around or otherwise secured around these members tightly enclosing them.

When these compartments are formed around a central compartment the sheath or binder will be substantially hexagonal in 100 section and it should be noted that a plurality of wedge shaped spaces 18 are formed between the tubular members and the sheath or binder.

The tubular members may be of any 105 length and may be cut to the proper length either before or after they are bound.

If desired the receptacle or container may comprise a plurality of sections, A, B, C and D as shown in Fig. 1, the sections being separated by discs 19 formed of corrugated cardboard or any other desired material.

The ends of the receptacle are closed by means of covers 20. Fig. 3 shows a top plan view of a blank from which a cover is formed. This blank has projecting portions 21 and tabs 22. To form the cover the tabs 22 are folded with respect to the body portion of the blank about the fold lines 23 to the position shown in Fig. 4 and these tabs may be bent slightly more if desired to form an acute angle between the tabs and the body portion of the cover. When the cover is placed on the box the tabs 22 are inserted in the spaces between the tubular members 15 and the sheath or binder 17 and the edges 20 of the tabs are wedged tightly between the adjacent portions of the members 15 and the sheath as illustrated in Fig. 2. In this connection attention is directed to the fact that due to the shape of the tabs and the 25 openings in which they are inserted, the tabs will center themselves as the cover is placed on the receptacle. When the covers are so disposed the portions 21 project beyond the sheath or binder and to remove 30 the cover these projecting portions are engaged and the cover is lifted.

In the form of the receptacle illustrated in Fig. 1 corrugated cardboard discs 19 are placed at the ends of the receptacle beneath 35 the covers.

If it is desired to seal the receptacle the covers have formed therein openings 24 and the discs 19 and 20 have formed therein central openings 25. A cord 30 is passed 40 through the central compartment 16 and through the openings in the discs and the covers, the two ends of the cord being secured together as shown at 31. A label or seal 32 is then secured over the connected 45 ends of the cord. In order to open the receptacle it will be obvious that the cord must be broken or the ends untied and before the ends may be untied the seal 32 must be mutilated.

50 In Fig. 6 there is shown a receptacle formed of one section having seven compartments, the two covers being secured in position in the manner hereinbefore described.

55 From the foregoing description it will be seen that a simple and practical container has been described and that this container can be economically manufactured and will effectively withstand rough usage encountered in shipping.

60 Although one specific embodiment of the invention has been particularly illustrated and described it will be understood that the invention is capable of modification and that 65 further changes in the construction and in

the arrangement of the various cooperating parts may be made without departing from the spirit or scope of the invention as expressed in the following claims.

What I claim is:—

70 1. A box having a plurality of compartments, and a binder or body portion surrounding said compartments, wedge shaped openings being formed between the body portion and the compartments and a cover for the box having projections adapted to extend into said openings, whereby the sides of the projection will be engaged by the compartments and body portion.

75 2. A box having a plurality of tubular compartments and a binder or body portion surrounding and tightly enclosing said compartments, wedge shaped openings being formed between the body portion and the compartments and a cover for the box having projections adapted to extend into said 80 openings, whereby the sides of the projection will be engaged by the compartments and body portion.

85 3. A box having a plurality of compartments, and a binder or body portion surrounding said compartments, wedge shaped openings being formed between the body portion and the compartments and a cover for the box having projections adapted to 90 extend into said openings, whereby the sides of the projection will be engaged by the compartments and body portion, said cover having a portion projecting laterally beyond the end of the binder or body portion of 95 the box.

100 4. A box comprising a plurality of tubular members, a sheath extending around and tightly enclosing said tubular members and covers at the end of said box having laterally projecting portions or flanges, the sides of which are engaged by the tubular members and sheath.

105 5. A box comprising a centrally disposed tubular member, a plurality of tubular members disposed around said centrally disposed member, a sheath disposed around and tightly engaging said outer tubular members and covers for closing the ends of the sheath and the ends of the tubular members, said covers having laterally projecting portions or flanges, the sides of which are engaged by the sheath and the outer portions of the tubular members.

110 6. A box comprising a plurality of sections disposed end to end, each of said sections having a central tubular member and a plurality of tubular members surrounding said central member, spacers disposed between each pair of said sections, each spacer having a central opening therein, a cover disposed at each end of the box and having a central opening therein, and a flexible securing member extending longitudinally through the central tubular members 115 120 125 130

through the spacers and through the covers and having its ends secured together.

7. A box comprising a body portion, means within the body portion forming a plurality of wedge shaped openings between said means and said body portion, and a cover for the box having projections adapted to extend into said wedge shaped openings, whereby the sides of the projections will be engaged by the body portion and the means within the body portion.

8. A box comprising a body portion, means within the body portion forming a

plurality of wedge shaped openings between the body portion and said means, and a cover for the box having tabs corresponding in number to the number of openings and adapted to extend into said wedge shaped openings whereby the sides of the tabs will be engaged by the body portion and the means within the body portion forming the openings.

In witness whereof, I have hereunto set my hand this 8th day of January, 1924.

HARRY B. CHALMERS.
